UNITED STATES PATENT OFFICE.

TOMAS PROCTOR HALL, OF VANCOUVER, BRITISH COLUMBIA, CANADA.

MOVING-PICTURE MACHINE.

1,156,596.

Specification of Letters Patent.

Patented Oct. 12, 1915.

Application filed January 15, 1912. Serial No. 671,341.

To all whom it may concern:

Be it known that I, TOMAS PROCTOR HALL, of the city of Vancouver, in the Province of British Columbia, Canada, have invented certain new and useful Improvements in Moving-Picture Machines; and I do hereby declare that the following is a full, clear, and exact description of the same.

10 This invention relates to an apparatus for projecting moving pictures without the objectionable flickering action and has for its object to provide a simple and improved construction for machines of this type as will be seen from the following description and claims.

For full comprehension, however, reference must be had to the accompanying drawings forming a part of this specification in which similar reference characters indicate the same parts and wherein:

Figure 1 is a plan view partly in horizontal section, of my improved apparatus, Fig. 2 is a vertical section taken on line 2—2 25 Fig. 1; Figs. 3 and 4 are enlarged detail views taken at right angles to each other and illustrating the construction of the reflecting device included in my invention; and Fig. 5 is a diagrammatic perspective 30 view of a portion of my apparatus.

My apparatus includes a reflecting device of particular arrangement and form whereby the image is reflected from the film directly to the screen upon which the pictures are being projected, thereby eliminating in machines of this type, the refracting substances heretofore placed intermediate of the reflecting surface and the screen.

Referring now to the drawings the housing is indicated at *b* and incloses the reels *c* and *d* upon which the film is wound, passing over rolls *f* and *g* mounted on opposite sides of the front aperture *h* of the housing, the roll *g* having the usual pegs for engaging the perforations in the film and being in operative engagement with the driving wheel *i* by gear wheel *j*. The driving wheel is preferably rotated by a crank *k* extending outside the housing, a sprocket and chain connection *l* being provided between the driving wheel and the receiving wheel *d*, to move the film in the usual manner.

The film is illuminated from a point *m* outside the housing, the light passing 55 through the film *e* and double convex lens *m* to a reflecting device in line with the film

and preferably comprising a series of mirrors *n* adapted to move in unison with the film when the machine is operating. The mirrors which are substantially the same size as the image upon the film are set at an angle to their carrier and together form a reflecting surface the transverse axis of which is at an angle to the transverse axis of the film so that when they assume a position opposite the portion of the film being illuminated they are inclined away from the film with their surface disposed to deflect the illuminated image from the film to the screen at a point to one side of the film, 60 through a second aperture *3* in the front of the housing at the side of and in a straight line with the aperture *h* (see Fig. 1). The lens *m* may be supported in a frame 2 secured to one side wall of the housing 75 and is inclined to assume a position parallel with the mirror then in line with the image being illuminated.

To insure the surface of the mirrors (which in the present instance are plane 80 but may be convex to form mirror lenses) coming into proper position relatively to the film that is with the side lines of the mirrors parallel with the side lines of the film, I have placed each one at a slight angle 85 to the adjoining ones as indicated in Figs. 2 and 3.

The mirrors are mounted on a wheel *o* rotatably supported in the center line of the apertures between the side walls of the housing and presenting near its periphery a circular angularly disposed flange *p* to which is secured a ring *q* of channel-cross-section and facing outwardly within which the mirrors are located, being held in position by 90 lugs *r* upon the ring *q* and by set screws *s*.

In the utilization of the wheel *o* as the carrier for the mirrors the desired inclination of the latter is obtained by inclining them inwardly in the longitudinal axial line 100 of the wheel such position being rigidly maintained by any preferable means as by extending the base of the ring *q* and placing a packing member *t* between the back of the mirrors and the wall of the ring. 105

The radius of the wheel *o* is preferably twice the distance between the film and the lens and the periphery of the wheel is provided with teeth *u* which engage with the teeth of the driving wheel *i* so that the movement of the mirrors upon such wheel is approximately the same as that of the film,

the idler *g* being on the opposite side of the wheel *i* to that of the wheel *o*.

The operation of my apparatus is as follows: The light from *x* passes through the film and lens thus projecting the image from

- 5 the film to one of the inclined mirrors *n* the image being then deflected to one side of the film again through the lens *m* and through the aperture *z* to the screen, the reels, etc., 10 being so arranged that they do not interfere with the rays, as will be clearly seen in the drawings. As the mirrors are moved in unison with the film the movement of the former is compensated for by the movement 15 of the latter thus when an image is projected by one of the mirrors, the image is stationary until it is gradually displaced and replaced by the image of the next portion of the film coming into the focus of the next mirror and so deflected upon the screen.

- 20 Thus two partial images deflected from two adjacent mirrors combine to form a complete image upon the continuously illuminated screen.
- 25 Although I have described my invention as applied to a projecting apparatus it will be apparent that it may be utilized to advantage in photographing moving objects by closing the aperture *h*, the mirrors *n* then reflecting the object from the exterior of the 30 housing to a sensitized film.

What I claim is as follows:—

1. In a moving picture machine, the combination with a housing, an aperture therein, and a film adapted to pass across the aperture, of a reflecting device situated within the housing and presenting a reflecting surface, opposite to and moving in unison with the portion of the film opposite to the aperture, the transverse axis of the said reflecting surface being at an angle to the transverse axis of the film and adapted to deflect an image from the film to one side of the line of travel of the latter, and a lens between 45 the film and the reflecting device, and adapted to be traversed by the incident and reflected rays.

2. In a moving picture machine, the combination with a housing having an aperture therein, and a film adapted to pass across the said aperture, of a single reflecting surface comprising a revolving series of mirrors all similarly inclined in the longitudinal line of a common axis and adapted to 55 deflect an image from the film to one side of the said aperture, and a lens between the film and the mirrors.

3. In a moving picture machine the combination with a housing having an aperture therein, and a film adapted to pass across the said aperture, of a reflecting device including a wheel rotatably mounted within the housing and a single series of mirrors carried by the wheel and inclined in the longitudinal axial line of the latter to deflect an

image from the film to one side of the said aperture, a double convex lens between the film and the mirrors and lying parallel to the latter, and operating means for simultaneously moving the film and the wheel.

4. In a moving picture machine the combination with a housing having two parallel apertures at the front thereof, and a film adapted to pass across one of the said apertures, a reflecting device including a wheel 70 rotatably mounted opposite the center of said apertures and having gear teeth upon the periphery thereof, a ring of channel-cross section mounted upon the wheel, a series of adjoining mirrors exposed to the film 75 and mounted within the ring, being set at an angle to each other and inclined inwardly in the longitudinal axial line of the wheel, a lens between the film and the mirrors and lying parallel with the latter, a gear wheel 80 operated from the exterior of the housing and intermeshing with the teeth of the mirror carrying wheel and an operative connection between the gear wheel and one of the 85 said reels, substantially as described and for the purpose set forth.

5. The combination with a moving film, of a reflecting device reflecting an image from the film, a lens common to and in the path of both the incident and reflected rays 90 and means for moving the reflecting device in unison with the film.

6. The combination with a moving film, of a device for reflecting an image from the film directly to one side thereof, a lens common to and in the path of both the incident and reflected rays and means for moving the reflecting device 100 in unison with the film.

7. The combination with a moving film, 105 of a reflecting surface whose transverse axis is at an angle to the transverse axis of the film, such surface reflecting an image from the film, a lens common to and in the path of both the incident and reflected rays and means for moving the reflecting surface in 110 unison with the film.

8. The combination with a moving film, of a suitably supported wheel, a ring of channel cross-section carried by the wheel and disposed substantially parallel to the 115 axial line of the latter, mirrors inclined at a common angle, held within and extending from side to side of the said ring and adapted to reflect an image from the film directly to one side of the film and means for rotating the mirrors in unison with the film.

9. In a moving picture machine, the combination with a housing having two apertures in the front thereof, a pair of reels and a film adapted to pass across one of the said apertures from one reel to the other, of a reflecting device including a wheel mounted opposite the center of one of said apertures, having gear teeth upon the periphery thereof and adapted to be rotated in unison with 120 125 130 135

- the movement of the film, a ring of channel cross-section mounted upon the wheel, a single series of adjoining mirrors exposed to the film and mounted within the ring, being 5 set at an angle to each other and inclined inwardly in the longitudinal axial line of the wheel, a double convex lens between the film and the mirrors and lying parallel with the latter, a gear wheel operated from the 10 exterior of the housing and intermeshing with the teeth of the mirror carrying wheel and an operative connection between the gear wheel and one of the said reels, substantially as described and for the purpose 15 set forth.
10. In a moving picture machine, the combination with a wall or partition having an aperture therein, of a pair of reels on one side of the partition and upon opposite sides 20 of the aperture, a film adapted to pass across the aperture from one reel to the other, illuminating means on the opposite side of the partition and adapted to direct light rays through the aperture and film and a 25 reflecting device having the film between it and the partition, such device moving in unison with the film and reflecting the light, subsequent to the passing of the same through the film, back to the opposite side 30 of the partition.
11. In a moving picture machine, the combination with a wall or partition having an aperture therein, of a pair of reels on one side of the partition and upon opposite sides 35 of the aperture, a film adapted to pass across the aperture from one reel to the other, illuminating means on the opposite side of the partition and adapted to direct light rays through the aperture and film, a reflecting 40 device having the film between it and the partition, such device moving in unison with the film and reflecting the light, subsequent
- to the passing of the same through the film, back to the opposite side of the partition and a lens located between the film and reflecting device and in the path of the light rays from both the film and reflecting device. 45
12. In a moving picture machine, a reflecting device comprising a suitably supported wheel, a ring of channel cross-section 50 carried by the wheel, facing outwardly and disposed substantially parallel to the axial line of the wheel and mirrors located between the flanges of the ring.
13. In a moving picture machine, a reflecting device comprising a suitably supported wheel, a ring of channel cross-section carried by the wheel, facing outwardly and disposed substantially parallel to the axial line of the wheel and mirrors located 55 between and inclined inwardly from the inner to the outer flange of the ring.
14. In a moving picture machine, a reflecting device comprising a suitably supported wheel, a circular flange upon the 60 wheel and extending outwardly therefrom in the axial line of the latter, a ring of channel cross-section secured to the flange, such ring facing outwardly from the flange and being disposed substantially parallel to the 65 axial line of the wheel, mirrors inclined toward the axis of the wheel and located between the inner and the outer flange of the ring, a packing member between the lower 70 ends of the mirrors and the ring and set-screws passed through the ring and engaging the mirrors to hold the latter in position. 75
- In testimony whereof, I signed my name to this specification, in the presence of two subscribing witnesses.

TOMAS PROCTOR HALL.
